LIQUID DISPENSER

Pete Lieuwen, New Holland, S. Dak.

Application October 3, 1949, Serial No. 119,270

4 Claims. (Cl. 222—90)

1

This invention relates to novel and useful improvements in dispensers.

An object of this invention is to pierce a can or other container having a pierceable portion by means of a hollow member, as a tube, which has a sharpened end and then retain the tube in the container so that the contents of the container or can may be poured through the tube.

Another object of this invention is to seal the tube tight with the top of the can so as to prevent leakage while the contents of the can is being poured therefrom.

A further object of this invention is to resiliently retain the seal against the top of the can and at the same time maintain the tube fixed in the container.

Other objects and features will become apparent in following the illustrated form of the invention.

In the drawing:

Figure 1 is an elevational view of the device, portions being shown in sections to illustrate detail of construction;

Figure 2 is an elevational view of the container, such as a can, having the invention connected therewith, portions of the can being broken away to illustrate detail of construction; and;

Figure 3 is a sectional view taken substantially on the line 3—3 of Figure 2 and in the direction of the arrows.

Figure 4 is a fragmentary elevational view of one of the projections in a part of the tube on which the projection is disposed;

Figure 5 is a front view of the detail of construction shown in Figure 4.

The device may be employed in connection with any type of container, can or the like wherein it is found practical and desirable. A metallic can or container 10 is illustrated having a top 12.

A hollow member, as a tube 14 is provided with a sharp end portion 16 which is employed for piercing the top 12 of the can 10. Lateral openings 18 are provided in the tube adjacent the sharpened portion or sharpened end thereof so as to allow the contents of the can to be poured therethrough as well as through the open sharpened end of the device.

A seal 20 which is in the form of a resilient ring is disposed in a carrier or retainer 22. The ring is preferably rubber and has an inwardly extending concentric ring 24 integral or rigidly fixed therewith. The ring 24 is adapted to seat in the groove 26 which is formed peripherally of the tube 14.

The retainer 22 has an annular seat 28 formed

2

therein wherein the seal 20 is disposed. A flange 30 also forms a part of the retainer and forms an abutment for one end of the spring 32. The retainer as well as the seal has a central passage therein accommodating the tube 14.

The spring 32 seats on the abutment 30 and also on a shoulder, which may be formed by the washer 34, fixed to the exterior surface of the tube 14 and spaced from the retainer. Accordingly, the spring reacting on the tube and the retainer, constantly pushes the retainer together with the seal downwardly toward the top 12 of the can.

An upper limit stop 38 is fixed to the exterior surface of the tube 14 and disposed within the retainer 22. A lower limit stop 40 is also fixed to the exterior surface of the tube and on the other side of the groove 26 with respect to the stop 38. The function of the stop 38 is to limit the downward travel of the retainer 22 with respect to the tube. The function of the lower stop 40 is to limit the downward movement of the tube through the top 12 of the can.

A pair of projections 42 and 44 respectively are formed on the exterior surface of the tube below the stop 40. These projections are passed through openings 46 and 48 which are formed in the top 12 of the can as the tube is forcibly thrust therethrough.

In operation, the sharpened end 16 of the tube is pressed through the top 12 of the can. It is pushed inwardly until such time as the upper surface of the top 12 engages the stop 40. At that time, the recesses 46 and 48 are formed on opposite sides of the opening which is formed by the tube in the can top. Then, the tube 14 is rotated so that the upper surfaces of the enlargements or projections 42 and 44 engage the undersurface of the top 12. This holds the tube in place.

When the tube 14 has penetrated the top of the can an amount sufficient to have the upper surface of the top 12 strike the stop 40, the resilient seal 20 has been pushed upwardly against the force of the spring 32. Accordingly, the spring 32 forcing the retainer 22 downwardly constantly presses the seal 20 against the upper surface of the top of the can. This forms a substantially fluid tight seal and any leakage is received in the chamber 50 defined by the inside surface of the seal 20, outside surface of the tube 14 and the connecting membrane 52 which joins the ring or bead 24 with the body of the seal 20.

When it is desired to remove the device, it is only necessary to rotate it so that the projec-

tions 42 and 44 pass through the recesses or openings 46 and 48.

The specific structure of the projections 42 and 44 is of importance. Reference to Figures 4 and 5 show the actual structure best. The projection has a lower end tapering to a point, as at 60, but blending into the material of the tube 14. Moving upwardly on the projection 42 the smoothly surfaced projection grows larger to a maximum, as at 62. At this maximum width and thickness region there is the beginning of a taper in the opposite direction from that taper extending from the lower end 60 to the maximum point 62. However, the upper taper does not terminate in a point but rather in a shoulder 64.

As the tube is pressed through the top of the container 10, at the obvious part of the downward travel of the tube, the lower end portions 60 begin to spread the material of the top adjacent the opening formed in the top 12 for the passage of the tube 14. As the tube 14 is pressed downwardly slightly farther, the openings 46 and 48 are made larger until the maximum point 62 of each projection passes into the can.

Then, the projection 42 and the projection 44 are pushed further downwardly until such time that the tube 14 is rotated so that the shoulders 64 abut the undersurface of the top 12 of the container 10.

In removal of the device from the container 10, the spring 32 assists. The tube 14 is rotated until such time that the projections 42 and 44 may pass through the openings 46 and 48. Since the taper from the shoulder 64 to the maximum thickness region 62 is formed so that the smaller part is adjacent the shoulder and the larger part is downward thereof, this taper acts in the nature of a guide whereby the projections are passed through the openings 46 and 48 very easily, as assisted by the spring 32.

Having described the invention, what is claimed as new is:

1. A can opener and dispenser comprising a hollow member constituting a spout and having a sharp cutting end, said member having a peripheral groove, a pair of spaced stops carried by said member with said groove between said stops, a seal disposed on said member and adapted to engage the can, said seal having a ring disposed in said groove, a carrier for said seal disposed on said hollow member with one stop adapted to engage the carrier to limit the relative travel of the carrier and the hollow member, the other stop being located above the lower edge of said seal and adapted to engage the can to limit the penetration into the can.

2. A can opener and dispenser comprising a hollow member constituting a spout and having a sharp cutting end, said member having a peripheral groove, a pair of spaced stops carried by said member with said groove between said

stops, a seal disposed on said member and adapted to engage the can, said seal having a ring disposed in said groove, a carrier for said seal disposed on said hollow member with one stop adapted to engage the carrier to limit the relative travel of the carrier and the hollow member, the other stop being located above the lower edge of said seal and adapted to engage the can to limit the penetration into the can, and a spring reacting on said hollow member and said carrier to press said seal against the can.

3. A can opener and dispenser comprising a hollow member constituting a spout and having a sharp cutting end, said member having a peripheral groove, a pair of spaced stops carried by said member with said groove between said stops, a seal disposed on said member and adapted to engage the can, said seal having a ring disposed in said groove, a carrier for said seal disposed on said hollow member with one stop adapted to engage the carrier to limit the relative travel of the carrier and the hollow member, the other stop being located above the lower edge of said seal and adapted to engage the can to limit the penetration into the can, and a spring reacting on said hollow member and said carrier to press said seal against the can, and means carried by said hollow member below said seal for releasably retaining said hollow member fixed to the can.

4. A can opener and dispenser comprising a hollow member constituting a spout and having a sharp cutting end, said member having a peripheral groove, a pair of spaced stops carried by said member with said groove between said stops, a seal disposed on said member and adapted to engage the can, said seal having a ring disposed in said groove, a carrier for said seal disposed on said hollow member with one stop adapted to engage the carrier to limit the relative travel of the carrier and the hollow member, the other stop being located above the lower edge of said seal and adapted to engage the can to limit the penetration into the can, and a spring reacting on said hollow member and said carrier to press said seal against the can, and a pair of projections on said hollow member for engaging the inside surface of the can top when the member is rotated after passing through the lid to clamp said member in the can.
